(57) **CLAIM**

The ornamental design for a car charger, as shown and described.

DESCRIPTION

FIG. 1 is a first perspective view of a car charger comprising a first component and a second component showing my new design;

FIG. 2 is a second perspective view thereof;

FIG. 3 is a first perspective view of a first component of a car charger shown separately for ease of illustration;

FIG. 4 is a second perspective view thereof;

FIG. 5 is a third perspective view thereof;

FIG. 6 is a fourth perspective view thereof;

FIG. 7 is a first perspective view of a second component of a car charger shown separately for ease of illustration;

FIG. 8 is a second perspective view thereof;

FIG. 9 is a third perspective view thereof; and,

FIG. 10 is a fourth perspective view thereof.

The broken lines present in the drawings are included for the purpose of illustrating portions of the article which form no part of the claimed design.

1 Claim, 10 Drawing Sheets
